US0D1091120S

(12) United States Design Patent (10) Patent No.: US D1,091,120 S
(45) Date of Patent: * Sep. 2, 2025

(54) HANDBAG

(71) Applicant: AZZEDINE ALAIA SAS, Paris (FR)

(72) Inventor: Pieter Mulier, Paris (FR)

() Term: 15 Years

(21) Appl. No.: 35/522,708

(22) Filed: Jul. 22, 2024

(80) Hague Agreement Data

Int. Filing Date: Jul. 22, 2024

Int. Reg. No.: DM/241032

Int. Reg. Date: Jul. 22, 2024

Int. Reg. Pub. Date: Oct. 18, 2024

(30) Foreign Application Priority Data

Jan. 23, 2024 (EM) 015048210-0001

(51) LOC (15) Cl. 03-01

(52) U.S. Cl.

USPC D3/246; D3/232

(58) Field of Classification Search

USPC ..... D3/232, 243, 244, 245, 246, 230, 231, D3/233, 242, 285, 286, 287, 289, 900, D3/205, 226, 301, 303, 304, 234, 306, D3/307, 308, 309, 239, 322; D14/440 CPC A45C 1/00; A45C 1/02; A45C 3/06; A45C 3/10; A45C 13/083; A45C 11/00; A45C 13/1076; A45C 1/04; A45C 1/08; A45C 13/02; A45C 13/1069; A45C 3/04; A45C 13/30; A45C 13/26; A45F 3/02; D06F 95/002
